OF NEW YORK, N. Y., A CORPORATION OF NEW YORK.

DOWNDRAFT WET PRECIPITATOR.

1,329,844.

Specification of Letters Patent.

Patented Feb. 3, 1920.

Application filed November 26, 1917. Serial No. 204,020.

To all whom it may concern:

Be it known that I, ARCHIBALD F. MESTON, a citizen of the United States, residing at New York, in the county of New York and State of New York, have invented certain new and useful Improvements in Downdraft Wet Precipitators, of which the following is a specification.

The present invention relates generally to 10 the class of apparatus for separating suspended particles in gaseous bodies by the application of electric discharges and more in particular to apparatus of that class in which gases or gaseous mixtures are subjected to a preliminary treatment for the purpose of promoting the separation of the suspended particles from the gaseous bodies.

The object of the invention is to treat 20 gases or gaseous mixtures preliminary to electric treatment in a precipitator with a fluid agent to thereby put the gases, gaseous mixtures or particular gaseous constituents into a favorable condition for the electrical treatment.

25 It is the particular object to bring a fluid agent in a finely divided condition into a near-molecular contact with a gas or gaseous mixture to be treated to thereby promote the susceptibility of the gas or gaseous mixture to electrical treatment.

To carry out these objects I make provisions whereby the fluid agent is caused to intercept a gas stream as a whirling or churning body of finely divided particles 35 and the resulting mixture in this condition of intimate near-molecular contact is immediately thereafter subjected to the action of a silent glow or electrical discharge in a precipitator.

40 For a fuller understanding of the invention I refer to the appended drawings in which—

Figure 1 is a view in side elevation of an apparatus embodying the principles of the 45 invention;

Fig. 2 a vertical section through the apparatus shown in Fig. 1; and

Fig. 3 a horizontal section on line 3—3, Fig. 1.

50 The precipitator structure comprises a skeleton frame constructed in any suitable way as of upright beams 1 interconnected by guy wires 2, a collecting electrode system consisting of a plurality of vertical tubes 3 supported by transverse webs 4 on the frame

and a discharge electrode system consisting of wires 5 extending through the tubes or pipes 3. I have shown tubes and wires, which form the treating chambers, merely as an illustration of the usual form of discharge chambers. Both the collecting electrodes and discharge electrodes may be constructed in different ways. Above the collecting electrode system is provided a closed chamber 6 extending substantially across 65 the whole frame and communicating with the tubes 3. The only access to this chamber from the outside is through an inlet 7 through which the gases are conducted into the precipitator.

70 The discharge electrodes are suspended from a common frame 8 located above the chamber 6 and supported on insulators 9 resting on the frame. Centrally on the frame 8 is supported a rod 10 extending through an insulator 11 into the chamber 6 and carrying at its lower end a transverse frame 12 to which all the discharge electrodes are connected. At their lower ends the discharge electrodes are connected to a 80 spacing frame 13 which is held in fixed position relatively to the general structure and the collecting electrodes in particular by insulators 14. These insulators may be attached to the skeleton frame in any suitable 85 way as by insulating blocks 15. Weights 16 are preferably attached to the lower ends of the wires 5 to hold them taut. The portion below the collecting electrodes is 90 enclosed to form a chamber 17 similar to chamber 6 and has an outlet 18 through which the treated gas is passed to a smokestack (not shown). At the bottom the chamber 17 is connected to the outside through a liquid seal 19 through which the material 95 collected may be drawn off without allowing the gases to pass out.

95 In the chamber 6, which I term the mixing chamber, I have placed a system of nozzles 20 connected to a liquid supply as for instance water by a pipe 21 which may be controlled by a valve 22. These nozzles are so constructed and disposed as to produce conjunctively a fine spray uniformly distributed across the chamber 6 to intercept 100 the entire gas stream, thoroughly mix with it and the suspended particles. The nozzle 20 may be disposed in various ways to insure a thorough mixing of the spray with the gases, but I have found that the arrange- 105 110

ment shown in Figs. 2 and 3 gives particularly good results, since the impact of the atomized particles of liquid on the gas stream and the particles suspended therein, 5 due to the uniformly angular position of the nozzles relatively to each other, sets up a whirling or churning motion at right angle to the tubes 3.

The tubes or pipes 3 have preferably a 10 flaring mouth at the upper as well as the lower end. It has been found that an excess of liquid suspended in the gases at the upper end and an agglomerate of precipitated particles at the lower end is likely to cause undesirable disruptive discharges. By expanding 15 the pipes 3 this contingency is practically obviated.

The spray is normally so adjusted by 20 means of the valve control 22 that after thorough mixing an excess of the finely divided liquid particles coalesces to cause a film or thin sheet of liquid to continuously run down the walls of the collecting electrodes. The heavy charge of atomized liquid 25 increases considerably the specific gravity of the gaseous mixture and this factor together with the kinetic energy of the gases developed in a downward direction facilitates the precipitation of the suspended particles. 30 The above can be illustrated by describing the use of the apparatus for removing from a gaseous mixture the soot or carbon black arising from a bituminous coal burning furnace.

35 As it is well known, the soot particles given off when coal is burned, leave the fuel in a finely divided state, probably approaching the molecular in size, but they tend to agglomerate as they are carried through the 40 furnace flues. Imperfect combustion of bituminous coal also gives off tarry particles, especially at those portions of the fuel bed where the temperature is comparatively low. These tarry particles combine or agglomerate 45 with the soot particles but the resulting material is in very fine state of subdivision even when leaving a smoke stack as the familiar "black smoke." It is an extremely difficult matter to wet fine soot particles 50 with water when they are mixed with water in the usual ways; especially is this true when the particles are coated with tarry substances.

When, as before described, the gases are 55 intermixed with the mist produced by the atomized water, all that is needed is some action to bring the suspended particles and the atomized water together. If there is a pronounced affinity of the particles for the 60 liquid this will come about rapidly and without the introduction of special methods. In the case of tarry soot and water mist, however, this does not occur and special means are necessary to bring about the wetting of 65 the particles. This is accomplished in the

apparatus described by the use of an electric field and preferably by the additional use of a corona discharge accompanying the electric field. In the discharge chambers where this wetting occurs the particles of 70 water and the suspended soot particles are both removed from the gases by action of the electric field and are thrown against the collecting electrodes, *i. e.*, the walls of the tubes 3, and are intimately mixed on the 75 surface thereof. The removed material would normally adhere to the collecting electrodes but in this apparatus the excessive water present forms a continuously running film on the surface of the collecting 80 electrodes and washes the deposited material down into the sump 19. This apparatus also permits the use of the phenomenon of water particles becoming nuclei for ions and thereby becoming more actively attractive to suspended particles, thereby wetting them and removing them from the gases. 85

Incidentally the liquid has the advantages of giving the gases better electric characteristics and adds materially to the success of 90 the process of removing the suspended particles.

The above described manner of treating 95 gases has particular utility in connection with electrical precipitation for the collection of combustible materials which ordinarily would catch fire from the electric discharge in precipitators as ordinarily operated. By the intimate mixture of such materials with a spray of a non-inflammable 100 liquid, such as water for instance, the danger is avoided.

In the claims, in the absence of a better term, I use the term "non-wettable" to define the characteristic of a certain class of 105 substances which do not have an affinity for water and therefore are not readily wetted when brought into contact with water or other suitable liquid.

I claim:—

1. The method of removing suspended 110 particles from gases which consists in adding a liquid in the form of a mist to the gases and subjecting the gases and mist to the action of an electric field.

2. The method of removing suspended 115 particles from gases which consists in adding to the gases liquid in finely divided form and in greater quantity than will be evaporated at that temperature of the gases which 120 will result from the addition of said liquid and then subjecting the gases to the action of an electric field.

3. The method of removing suspended 125 particles from gases which consists in passing the gases through a zone of finely divided liquid, supplying the liquid at a rate which is in excess of that at which the liquid is evaporated under prevailing temperature conditions of the gases and subjecting the 130

mixture of gases and liquid to the action of an electric field.

4. The method of removing suspended solid particles from gases which consists in spraying the gases with liquid and passing the mixture of gases and suspended solid and liquid particles into an electric field.

5. The method of removing solid particles from gases which consists in introducing liquids into the gases in finely divided form, electrically precipitating the solid and liquid particles simultaneously to form a sludge.

6. The method of removing solid particles from gases which consists in introducing liquids into the gases in finely divided form, electrically precipitating the solid and liquid particles simultaneously to form a sludge and recovering said sludge by gravity settling.

7. The method of removing non-wettable particles from gases, which consists in adding a liquid in the form of a mist to the gases containing the particles in suspension and subjecting the gases and mist to the action of an electric field.

8. A method of removing suspended particles from smoke, which consists in adding a liquid in the form of a mist to the smoke and subjecting the smoke and mist to the action of an electric field.

9. The method of removing non-wettable particles from a gas, which consists in adding a liquid in the form of a mist to the gases containing the particles in suspension in such a way as to intimately mix the gas and the mist and then subjecting the mixture to the action of an electric field.

10. The method of removing suspended particles from smoke, which consists in adding a liquid in the form of a mist to the

smoke in such a way as to intimately mix the smoke and the mist and then subjecting the mixture to the action of an electric field.

11. In an apparatus for treating gaseous bodies, the combination with a vertically disposed electrical discharge chamber, of a gas receiving chamber immediately above the discharge chamber, means for discharging a fluid into the receiving chamber in a finely divided condition, and means for mixing the incoming gas and the said fluid.

12. In an apparatus for treating gaseous bodies, the combination with a vertically disposed electrical discharge chamber, of a gas receiving chamber immediately above the discharge chamber, means for discharging a liquid into the receiving chamber in a fine spray, and means for mixing the incoming gas and the said liquid spray.

13. In an apparatus for treating gaseous bodies, the combination with a vertically disposed electrical discharge chamber, of a gas receiving chamber immediately above the discharge chamber, means for discharging a fluid into the receiving chamber in a finely divided condition and in the form of a whirl intercepting the flow of gas, said means comprising a system of nozzles disposed in the receiving chamber in symmetrical angular relation to each other.

14. In apparatus for separating suspended particles from smoke, the combination with a vertically disposed discharge chamber, of a smoke-receiving chamber immediately above the discharge chamber, means for discharging a liquid into the receiving chamber in a finely divided spray, and means for mixing the incoming smoke and the said liquid.

In testimony whereof I affix my signature.
ARCHIBALD F. MESTON.
